UNITED STATES PATENT OFFICE.

ANTHONY SCHROEDER, OF CLEVELAND, OHIO, ASSIGNOR OF ONE-HALF TO JAMES MERLE FINNEY, OF CLEVELAND, OHIO.

SEAMING MACHINE.

Application filed April 12, 1920. Serial No. 373,040.

To all whom it may concern:

Be it known that I, ANTHONY SCHROEDER, citizen of the United States, residing at Cleveland, in the county of Cuyahoga and 5 State of Ohio, have invented certain new and useful Improvements in and Relating to Seaming Machines, of which the following is a specification.

This invention relates to a machine for 10 securing heads on metal bodies to form drums, and particularly to a machine for folding together or seaming the flanges on the heads and bodies thereof.

One object of the invention is to increase 15 the output of machines of this character.

Another object of the invention is to reduce the number of operatives required to 20 operate machines of this character at full capacity and to simplify the required manual operations, whereby relatively cheap or unskilled labor may be employed to operate them.

Another object of the invention is to provide improved means for supporting, operating and controlling the seam forming rolls 25 of machines of this character, whereby the seaming operations may be rapidly completed, the heads securely fixed to the drum bodies and the rolls returned to their inoperative positions upon the completion of 30 their respective operations.

Other objects of the invention will be apparent to those skilled in the art to which my invention relates from the following description taken in connection with the accompanying drawings.

Referring to the drawings, Fig. 1 is an elevational view of a seaming machine embodying my invention.

Fig. 2 is a horizontal section of the machine on the line 2—2 of Fig. 1.

Fig. 3 is a plan view of the seaming rolls and mechanism for operating and controlling them.

Fig. 4 is an elevational view of the parts shown in Fig. 3.

Fig. 5 is a sectional view on the line 5—5 of Fig. 3.

Fig. 6 is a sectional view on the line 6—6 of Fig. 3.

Fig. 7 is a sectional view on the line 7—7 of Fig. 3.

Fig. 8 is a section on the line 8—8 of Fig. 7.

Fig. 9 is a sectional view on the line 9—9 of Fig. 3.

Fig. 10 is a section on the line 9—9 of Fig. 3 showing the operation of the first seaming roll.

Fig. 11 is a section on the line 11—11 of Fig. 3 prior to its engagement with the partially formed seam.

Fig. 12 is a section on the line 11—11 of Fig. 3 showing the final seaming roll in position for completing the seam between the head and drum body.

Fig. 13 is a detail view.

Fig. 14 is an elevation of another form of seaming machine embodying my invention.

Fig. 15 is a side elevation of the machine shown in Fig. 14.

Fig. 16 is a top plan view of the seaming rolls and toggle members forming part of the machine shown in Figs. 14 and 15.

Fig. 17 is a fragmentary view of the machine, showing the parts illustrated in Fig. 16 in side elevation.

Fig. 18 is an end view of the parts shown in Fig. 16.

Fig. 19 is a rear end view of the parts shown in Fig. 17.

Fig. 20 is a section on the line 20—20 of Fig. 16.

Fig. 21 is a section on the line 21—21 of Fig. 16.

Fig. 22 is a transverse section through the elements shown in Fig. 16.

In the drawings, 1 indicates as an entirety a frame. The frame 1 may comprise a table 90 or bed 2, supported on suitable legs 2^a, and a pair of upright members 3 connected at their upper ends by a cross member 4. The members 3 may be spaced to receive between them the largest sized drum desired to be 95 made on the machine. The frame 1 may also be provided with a member 5 extending laterally from one side of the machine.

The elements of the frame, just referred to, may be integrally connected or otherwise 100 formed. At its remote or outer end, the extension member 5 is provided with an upright shaft hanger 6, provided with bearings 7. The bearings 7 and bearings 8 provided on the adjacent end of the table 2, support a shaft 9, the purpose of which will be later set forth.

10 indicates a vertical shaft mounted in

- 2
- suitable bearings provided centrally of the table 2. 11 indicates a gear fixed to the shaft 10. The gear 11 is preferably a bevel gear and is driven by a bevel pinion (not shown) on the inner end of the shaft 9. 12 indicates as an entirety the driving means for the shaft 9. The driving means 12 preferably comprise a pulley 12^a, loosely mounted on the shaft 9, and clutch elements 13. 10 One clutch element is fixed to the pulley 12^a; the other clutch element is splined to the shaft 9 and connected with and released from the first mentioned element by a lever 14, in a well known manner. 15 15 indicates a base member supported on the table 2. The base member 15 is so shaped and constructed that it encloses the gear 11 and driving pinion therefor. Centrally, the base member 15 is formed with an opening through which the shaft 10 and hub member thereon extends. The base member 15 may be provided with an integral, radially extending bracket 16, the purpose of which will be later set forth. 20 25 17 indicates a support connected to the upper end of the shaft 10 and arranged to receive the drum body, indicated at A, and the head, indicated at a, to be seamed thereto. The support 17 is of less diameter than the drum body or drum head in order that the seaming operations, to be later described, may be carried out without danger of engagement with the support 17. The support 17 is preferably detachably connected to the shaft 10 so that it may be removed and a support of a different diameter substituted according to the size of the drum to be made at any time. 30 35 40 45 50 55 60 65 18 indicates a plate adapted to engage the upper end of the drum body A and hold it and the head a firmly on the support 17. The plate 18 is fixed to the lower end of a rod 19 slidably mounted in guides 20, which are provided on the cross member 4, and bearings 21 provided on a cross piece 22. The cross piece 22 is connected at its opposite ends to the upright frame members 3. The rod 19 preferably comprises a sleeve 19^a having internal screw threads and a screw thread member 19^b fitting therein, whereby the rod 19 can be lengthened or shortened to accommodate it to different sized drums. The sleeve 19^a and member 19^b are fixed or secured together by nuts 19^c, 19^{c'}. Near its upper end the sleeve 19^a is provided with a grooved collar 23, in the groove of which are disposed the bifurcations on the end of a lever 24. The lever 24 is pivoted in any well known manner, preferably on a bracket 24^a, on the cross member 4 and counterbalanced at its outer end, as shown at 25. 26 indicates devices for operating the lever 24 about its pivot to raise and lower the rod 19. The lever is raised to disengage the plate from the drum (see dotted lines in Fig. 1) and

thus permit the positioning of a drum body on the support 17 and its removal therefrom; it is lowered to move the plate 18 into engagement with the drum and thus clamp it firmly on the support 17 and hold the drum thereon during the rotation of the support and the forming of the seam. The devices 26 preferably comprise a pair of connected links 27, 27^a, connected at their remote ends to the lever 24 and a rock shaft 28, respectively. The rock shaft 28 is connected through an arm 28^a to a rod 29 which is operated by means 30, such as a compressed air operated piston, controlled by a lever 30^a. The collar 23 is preferably slidably mounted on the sleeve 19^a and normally held against the nut 19^c by a coiled spring 19^a interposed between it and a collar 19^c provided on the sleeve 19^a. The spring 19^a serves to yieldingly clamp the plate 18 against the drum body A. 70 75 80 85 90

The cross piece 22 is preferably so connected to the frame members 3 and 4 that it can be adjusted to different positions according to the size of drum to be seamed. 90 As these supporting and adjusting devices form no part of my present invention, a detail description thereof will not be necessary. 95

31 indicates a plurality of seaming rolls. I have provided my apparatus with two rolls 31^a, 31^b, which operate successively to effect and complete the operations of seaming a head a to the body A of a drum. The peripheries of the rolls 31^a, 31^b, are for illustrative purposes shown as being shaped to form what is known as a double seam, this being the preferred form of construction and the one mostly used in the manufacture of metallic receptacles. Each roll 31^a, 31^b, is loosely mounted on a vertical shaft 32 suitably supported at its opposite ends in a pair of arms 33, extending from the free end of a slide block 34. The slide blocks 34 are mounted in suitable guides 35, whereby they may be moved toward the drum body A and into engagement with the flanges of the body and head a therefor, and then returned to their inoperative positions. The guides are preferably formed integrally with a frame 36, which is supported on and rigidly secured to the bracket 16. 110 115 120

37 indicates as an entirety means connected to the slide blocks 34 for operating and controlling the seaming rolls 31^a, 31^b. Of these means, 38 indicates a shaft mounted in spaced bearings 38^a, 38^b, provided on the frame 36 and an arm 39 connected thereto. 40 indicates a belt wheel or pulley loosely mounted on the shaft 38 and preferably continuously driven by a belt 40^a. The inner end of the shaft 38 is mounted in bearings 44 provided in an angle plate 45, which is rigidly secured to the frame 36 in any desired manner. 46 indicates a clutch, the co- 125 130

operating elements of which are connected to the shaft 38 and pulley 40, whereby the shaft is driven by the latter when the clutch is connected or thrown in. The movable element of the clutch 46 is connected by links 46^a to an operating lever 47 which is secured to a rock shaft 48. 48^a indicates supporting members for the shaft 48, connected with the frame 36 in any desired manner. 49 indicates a cross shaft mounted at its opposite ends in suitable bearings provided in the side walls of the frame 36. Midway between its ends the shaft 49 is provided with a worm gear 49^a, which is driven by a worm 50 fixed to the shaft 38. 50^a, 50^{a'}, indicate a pair of cams fixed to the shaft 49, each preferably arranged in a vertical plane cutting the central longitudinal axis of the adjacent block 34. The cams 50^a, 50^{a'}, are set 20 angularly on the shaft 49, relatively to each other, to effect successive operation of the rolls 31^a, 31^b, and permit their withdrawal from engagement with the rolled flanges, as will be later set forth. 51, 51^a, indicate sets 25 of toggle members interposed between the slide blocks 34 and the cams 50^a, 50^{a'}, respectively and arranged to be actuated by the latter. Each set of toggle members 51, 51^a, preferably comprise a rocking element 52, loosely mounted on a transverse shaft 52^a, and a link 53 pivotally connected at its opposite ends to the rocking element 52 and adjacent slide block 34. That end of the rocking element 52 which is engaged by the adjacent 30 cam may be provided with a roller 54 to reduce the friction between the cam and rocking member.

As shown in the drawings, the slide blocks 34 are formed with a recess to receive a removable connecting member 55 to which the link 53 is connected. The connecting member 55 is secured in the recess of the slide block by any suitable means, that shown comprising cap screws 56 (see Fig. 3). This 45 form of construction provides a long bearing for the link 53 on the pivot between it and the connecting member 55.

As shown in the drawings, the edges of the cams 50^a, 50^{a'}, are flat and when rotated 50 engage the rear end of the rocking members 52 to successively rock them about the shaft 52^a and thereby operate through the links 53 to move the slide blocks 34 outwardly or toward the drum body A to position 55 the rolls 31^a, 31^b, carried thereby in operative position. The cams 50^a, 50^{a'}, are shaped to cause this operation, to then maintain them in operative position until their respective seam folding operations are completed 60 and to then permit their withdrawal to inoperative position. The cam 50^{a'} is preferably shaped to move the adjacent roll 31^b forward and maintain it in close proximity to the body A so that as soon as the roll 31^a 65 has completed its operation, it may be moved

into operative position without the loss of time. To effect the withdrawal of the rolls 31^a, 31^b, I prefer to provide a pair of coiled tension springs 57, one for each set of toggles. As shown, each spring is connected at one 70 end to a stationary part of the frame 36, preferably the upper free end of an arm 58; its opposite end is connected to the forward end of the adjacent rocking member 52, preferably by means of a hook member 59. The 75 springs 57 are so arranged that when the cams 50^a, 50^{a'}, operate the rocking members 52, from the positions shown in Figs. 9 and 11 to that shown in Figs. 10 and 12, respectively, they will be put under tension enabling them to move the rocking members 52 and through them the blocks 34 and rolls 31^a, 31^b, back to the starting or inoperative position.

The operation of the apparatus may be set 85 forth as follows.

The rolls 31^a, 31^b, are arranged in the inoperative position as shown in Figs. 3, 9 and 11. A head a is first placed on the supporting plate 17 and on the head a is placed 90 a body A. A second head a is preferably placed on the upper end of the body A and the clamping plate is brought down into engagement therewith. The clutch elements 13 are then connected up and the shaft 10 rotated. Next, the operative grasps the lever 47 and throws in the clutch 46 to operate the shaft 38, which in turn drives the cross shaft 49. At the time the shafts 10 and 49 are connected to their respective drive mechanisms, the rolls 31^a, 31^b, are in their inoperative positions and ready to be moved forward under the action of the cams 50^a, 50^{a'}. This position of the roll 31^a and the toggle members connected thereto and the cam 50^a for operating the toggle members 52 is shown in Fig. 9. As the cam 50^a rotates it moves these parts to the position shown in Fig. 10, whereupon the flanges of the head a and body A, (which are being rotated at this time by the shaft 10), will be folded together and relative to the body A as shown at a' in Figs. 10 and 11. The cam 50^a is shaped to maintain the roll 31^a in engagement with the flanges sufficiently long to complete this portion of the double seaming operation. At the end of this operation the rocking element 52 is released from the cam 50^a and under the influence of the spring 57 it and the adjacent block 34 and roll 31^a are moved rearwardly to the position shown in Fig. 9. Likewise, as the cam 50^{a'} rotates, its operative portion engages the rocking element 52 of the toggle members 51^a and through them and the adjacent block 34 moves the roll 31^b from the position shown in Fig. 11 to the position shown in Fig. 12, for engagement with the partly folded flanges. As a result of such engagement the roll 31^b operates to fold the

105
110
115
120
125
130

head and body flanges relative to each other and body A as shown in Fig. 12. As shown in this latter figure, the cam 50^a is shaped to first move the roll 31^b relatively close to the body A to roll the flanges upwardly and inwardly and then to move the roll closer to the body A the effect of which is to compress the folded sections of the flanges together into intimate contact, thus completing the double seam.

At the end of the last described operation, the toggle members 51^a are released by the cam and they then are moved to the inoperative position by the adjacent spring 57.

The cams 50^a, 50^{a'}, are so arranged angularly on the shaft 49 that the second operation above described follows immediately after the completion of the first operation, as already set forth, the cam 50^a being preferably shaped and arranged to move the roll 31^b forwardly while the roll 31^a is operating, see the eccentric portion designated 50^b, and then maintain it in close proximity to the drum, see the concentric portion marked 50^c, in order that the time required for completely double seaming a head *a* to a body A may be reduced to the shortest period of time possible.

59' indicates as an entirety means for automatically releasing the clutch members 46 to disconnect the shaft 38 from its driving means 40. These means are preferably provided in order that the rolls 31^a, 31^b, can be held in an inoperative position while the drum body A, after the completion of a double seaming operation, is being inverted on the plate 17 or the drum is being removed and a new body A and head *a* are being positioned thereon. Of these means, 60 indicates an arm fixed to the shaft 48. 61 indicates a latch pivoted upon one side of the arm 60 near its free end. The nose of the latch 61 extends forwardly and is disposed in the path of movement of a pin 61^a fixed to and extending laterally from one side face of the cam 50^a. 62 indicates a tension spring connected at its opposite ends to the arm 60 and latch 61 and operating to maintain the latch in the position shown in Figs. 11 and 12. 63 indicates a stop carried by the arm and arranged in position to be engaged by the tail of the latch 61. As the cam 50^{a'} rotates anti-clockwise, the pin 61^a will engage the latch 61 and swing it about its pivot until its tail engages the stop 63; thereupon, the further movement of the pin 61^a acting through the latch 61 and stop 63, will swing the arm 60 and rock the shaft 48 in a rearward direction, thus releasing the clutch 46 (see Fig. 13). The elements just referred to are arranged for co-operation after the seaming operation is completed.

Figs. 14 to 22, inclusive, illustrate a slightly modified form of my invention par-

ticularly adapted for double seaming the flanges of the heads and bodies of relatively small sized metallic receptacles. In this form of the invention the plate 18', which engages the upper head *a* of the drum, is secured to and driven by a shaft 10' suitably mounted in overhead bearings 63' carried by a standard 64 and driven by the power mechanism indicated as an entirety at 63^a; while the plate 17', which engages with and supports the lower head *a* and drum body A, is slideable endwise upwardly and downwardly, so as to clamp the drum against the plate 18' and release it therefrom. The plate 17' is preferably raised and lowered by a suitable lever mechanism, indicated at 17^a.

In such a construction, that is one wherein the upper head engaging plate 18' is driven, I prefer to so arrange the seaming rolls and their operating devices that they will operate upon the flanges of the head and the drum body at the upper end thereof.

Referring to these figures, 65 indicates a support or bracket preferably formed integral with the standard 64. 36' indicates a frame mounted on the support 65 and formed with a pair of parallel guides in which are slidably mounted a pair of blocks 34' carrying seaming rolls 31^{a'}, 31^{b'}, respectively. 51', 51^{a'}, indicate sets of toggle members, each interposed between the adjacent slide block 34' and a stationary abutment 66, fixed in any desired manner at the rear end of the frame 36'. Each set of toggle members preferably comprises a pair of links 67, 68, pivotally connected together at their inner ends, as shown at 69, and pivoted at their outer ends to the adjacent blocks 34', and abutment 66. The pivot connections for the inner and outer ends of the links 67, 68, may be of any preferred form.

70 indicates as an entirety means for operating the toggle members 51', 51^{a'}. Of these means 71, 71^a, indicate a pair of arms depending from the support 65 and frame 36' (see Fig. 19) and formed at their lower ends with openings which form bearings for a rock shaft 72.

73 indicates a sleeve shaft surrounding a portion of the shaft 72 and rotatably mounted in the opening of the adjacent arm 71. 74, 74^a, indicates a pair of cranks the hubs of which are secured to the shafts 73, 72, respectively, by set screws 75. 76, 76^a, indicates a pair of rods for connecting the cranks 74, 74^a, with the toggle members 51', 51^{a'}, respectively. As shown, each rod 76, 76^a, is pivotally connected at one end to the adjacent crank by a pintle 77, and at its opposite end it is preferably pivotally connected to the pivot pin 69 between the inner ends of the toggle links 67, 68.

78, 78^a, indicate hand levers connected in 130

any desired manner to the outer or free ends of the shafts 72, 73, respectively, whereby the latter may be rocked independently of each other.

5 Endwise movement of the shafts 72 and 73 in their bearings and relative to each other is prevented preferably by the following devices, to wit, a collar 78' fixed to the shaft 72 and engaging the outer side of the 10 arm 71^a; a collar 79 fixed to the shaft 73 and engaging the outer side of the arm 71; a collar 80 fixed to the shaft 72 and engaging the outer end of the sleeve shaft 73; and a spacing device 81 between the crank 74 and 15 inner side of the arm 71.

The rolls 31^{a'}, 31^{b'}, are similar in shape to the rolls 31^a, 31^b, respectively, and are operated successively in a like manner by means of the levers 78, 78^a.

20 I have found by experience that a relatively heavy pressure may be applied upon the head and body flanges to form double seams by or through the seaming rolls when the latter are operated by toggle members.

25 Accordingly I am enabled, in the use of my invention to rapidly double seam heads on drum bodies the metal of which is relatively thick gaged and at the same time bend and fold the metal into a tight seam and there- 30 by form a substantially leak-proof joint. I have also found that when the machine is constructed to be operated by hand levers, a substantially increased pressure can be transmitted through the toggle members to 35 the seaming rolls, so that I am enabled to double seam receptacles formed of thicker metal than was heretofore possible on machines of similar size and strength.

To those skilled in the art to which this 40 invention relates many alterations in construction and widely differing embodiments and applications of my invention will suggest themselves without departing from the spirit and scope thereof. My disclosures and 45 description herein are purely illustrative and are not intended to be in any sense limiting.

What I claim is:

1. In apparatus of the class described, the combination with a support on which 50 flanged barrel bodies and heads are adapted to rotate, of a pair of rolls each slidably mounted on said support and shaped to fold the flanges of the barrel bodies and heads relative to each other to form a seam or joint, pairs of toggle members for operating said rolls, and driven cams each engaging one member of each pair of toggle members for controlling the operation thereof.

60 2. In apparatus of the class described, the combination with a support on which flanged barrel bodies and heads are adapted to rotate, of a pair of rolls each slidably mounted on said support and shaped to 65 fold the body and head flanges relative to

each other to form a seam or joint, pairs of toggle members for operating said rolls, driven cams each engaging one member of each pair of toggle members for controlling the operation thereof, and means for stopping the operation of the cams at the end of the seaming operation. 70

3. In apparatus of the class described, the combination with a support on which flanged barrel bodies and heads are adapted to rotate, of a pair of rolls each slidably mounted on said support, and shaped to fold the body and head flanges relative to each other to form a seam or joint, pairs of toggle members for operating said rolls, driven 75 cams each engaging one member of each pair of toggle members for controlling the operation thereof, means for stopping the operation of the cams at the end of the seaming operation, and means for returning the toggle members and rolls to starting position. 80

4. In apparatus of the class described, the combination with a support on which barrel bodies and heads therefor are adapted to rotate, of a pair of rolls each slidably mounted on said support and shaped to fold the body and head flanges to form seams or joints, pairs of toggle members for operating said rolls, devices for moving said pairs of toggle members, and means operated by one of said devices for stopping them at the end of each seaming operation. 90

5. In apparatus of the class described, the combination with a support for flanged drum bodies and heads therefor, of a pair of rolls shaped to fold the flanges of a body and head relative to each other to form a seam, sets of toggle members connected to the supports for said rolls, means normally acting on said member to maintain them in inoperative position, a shaft, a pair of cams on said shaft arranged to engage said toggle members to operate them, whereby said rolls are moved into engagement with the flanges of the body and head to fold them into a seam. 100

6. In apparatus of the class described, the combination with a support for flanged drum bodies and heads therefor, of a pair of rolls each slidably mounted upon said support at one side of its axis and shaped to fold the flanges of a body and head relative to each other to form a seam, pairs of toggle members for operating the supports for said rolls, a shaft disposed in parallel relationship to the pivots of said toggle members, and a pair of cams secured to said shaft in alignment with said toggle members and engaging therewith to actuate them in co-operative relation, and means for driving said shaft. 115

7. In apparatus of the class described, the combination with a frame on which barrel bodies and heads are adapted to rotate, of a 120

pair of rolls mounted on supports slideable on said frame and shaped to fold the body and head flanges to form seams, pairs of toggle members for moving the roll supports to position the rolls for operation, each pair of toggle members comprising a rocking element pivoted intermediate its ends and a link connected at its opposite ends to one end of said rocking element and the adjacent roll support, and means engaging with the other end of each rocking element for operating said pairs of toggle members.

8. In apparatus of the class described, the combination with a frame on which barrel bodies and heads are adapted to rotate, of a pair of rolls mounted on supports slideable on said frame and shaped to fold the body and head flanges to form seams, pairs of toggle members for moving the roll supports to position the rolls for operation, each pair of toggle members comprising a rocking element pivoted intermediate its ends and a link connected at its opposite ends to one end of said rocking element and the adjacent roll support, and a cam engaging with the other end of said rocking element, whereby said pairs of toggle members are operated.

9. In apparatus of the class described, the combination with a frame on which barrel bodies and heads are adapted to rotate, of a pair of rolls mounted on supports slideable on said frame and shaped to fold the body and head flanges to form seams, pairs of toggle members for moving the roll supports to position the rolls for operation, each pair of toggle members comprising a rocking element pivoted intermediate its ends and a link connected at its opposite ends to one end of said rocking element and the adjacent roll support, a cam engaging with the other end of each rocking element, whereby said pairs of toggle members are operated in one direction, and separate means for returning said pairs of toggle members to starting position.

10. In apparatus of the class described, the combination with a frame on which barrel bodies and heads are adapted to rotate, of a pair of rolls mounted on supports slideable on said frame and shaped to fold the body and head flanges to form seams, pairs of toggle members for moving the roll sup-

ports to position the rolls for operation, each pair of toggle members comprising a rocking element pivoted intermediate its ends and a link connected at its opposite ends to one end of said rocking element and the adjacent roll support, a driven cam engaging with the other end of each rocking element, whereby the pairs of toggle members are operated, and means operated by one of said cams for stopping their operation at the end of each seaming operation.

11. In apparatus of the character described, the combination with a support for flanged barrel bodies and heads, of a pair of rolls shaped to fold the flanges of a barrel body and head relative to each other to form a seam, pairs of toggle members connected respectively to said support and one of said rolls for operating the latter, a shaft, cams on said shaft, each engaging one member of the adjacent pair of toggle members, and means for driving said shaft.

12. In apparatus of the character described, the combination with a support for flanged barrel bodies and heads, of a pair of rolls shaped to fold the flanges of a barrel body and head relative to each other to form a seam, a shaft, a pair of cams on said shaft, toggle members connected to the supports for said rolls and arranged to be operated by said cams in succession, means for driving said shaft, means acting on said toggles to move the rolls rearwardly as soon as each completes its operation, and means controlled by one of said cams for throwing out said driving means as soon as both rolls complete their operation.

13. In apparatus of the character described, the combination with a support for flanged barrel bodies and heads, of a pair of rolls shaped to fold the flanges of a barrel body and head relative to each other to form a seam, a shaft, a pair of cams on said shaft, toggle members connected to the supports for said rolls and arranged to be operated by said cams in succession, means for driving said shaft, and means controlled by one of said cams for throwing out said driving means as soon as both rolls complete their operation.

In testimony whereof I affix my signature.

ANTHONY SCHROEDER.
